US0D1104254S

(12) **United States Design Patent** (10) **Patent No.:** **US D1,104,254 S**
(45) **Date of Patent:** **** Dec. 2, 2025**

(54) **DRUG DELIVERY SYSTEM**

(71) Applicant: **JANSSEN BIOTECH, INC.**, Horsham, PA (US)

(72) Inventors: **Michael Cannamela**, Atlantic Highlands, NJ (US); **Jimmy Vinh Hoang Cassebee**, Fremont, CA (US); **Steven M. Vesole**, Redwood City, CA (US)

(73) Assignee: **Janssen Biotech, Inc.**, Horsham, PA (US)

(**) Term: **15 Years**

(21) Appl. No.: **29/920,394**

(22) Filed: **Dec. 11, 2023**

Related U.S. Application Data

(63) Continuation of application No. 29/832,830, filed on Mar. 30, 2022, now Pat. No. Des. 1,015,529.

(57) **CLAIM**

The ornamental design for a drug delivery system, as shown and described.

DESCRIPTION

FIG. 1 is a front-top-right perspective view of a drug delivery system showing our new design;
FIG. 2 is a right side view of the drug delivery system of FIG. 1;

FIG. 3 is a left side view of the drug delivery system of FIG. 1;

FIG. 4 is a bottom plan view of the drug delivery system of FIG. 1;

FIG. 5 is a top plan view of the drug delivery system of FIG. 1;

FIG. 6 is a front plan view of the drug delivery system of FIG. 1; and,

FIG. 7 is a back plan view of the drug delivery system of FIG. 1.

The broken lines shown in the views are included for the purpose of illustrating portions of the drug delivery system that form no part of the claimed design.

1 Claim, 7 Drawing Sheets
